UNITED STATES PATENT OFFICE

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY

METHOD AND MEANS FOR ERECTING MASTS

Application filed November 21, 1928. Serial No. 320,773.

The present improvements relate, in general, to the erection of sectional masts, towers and the like, and more particularly to the means for and method of erecting such vertical masts adapted for use in connection with the gravity distribution of loose materials such as concrete and the like. It is apparent however, that the present improvements may be employed in other fields of endeavor, 10 where similar masts are utilized.

A primary object, among others, is to provide a mast erection arrangement which employs a small number of parts, eliminates several attendants in supervising the work, and 15 reduces the steps to be practiced in the erection method to a minimum. A further object is to provide a novel erection mechanism adapted for use in connection with an erected section of a mast. The present improvements 20 further contemplate the provision of a novel erection mechanism, constructed and arranged to perform other services in addition to the erection functions ascribed thereto.

Other objects and advantages in the construction and arrangement of the present improvements will be apparent to those skilled in the art upon reference to the accompanying description and drawings in which—

Fig. 1 is a side elevation of the lifting frame, illustrating the first step in the method of erection;

Fig. 2 is a view taken at right angles to Fig. 1;

Figs. 3 and 4 are front and side elevations 35 respectively of a portion of the erected base section, illustrating another step in the method and additional parts;

Fig. 5 illustrates, in elevation, another step in the method;

Fig. 6 is a view similar to that of Fig. 5 illustrating the initial step in erecting a third section;

Figs. 7 and 8 are enlarged views of details;

Fig. 9 is an enlarged plan of the platform 45 support;

Fig. 10 is an enlarged side elevation of the platform support and frame thereof.

One application of the present improvements is illustrated and will be described in 50 connection with a mast plant for the gravity

distribution of loose materials, such as concrete and the like, a more detailed description of which may be found upon reference to the copending applications of John P. Faber filed August 5th, 1924, Serial Number 730,161, 55 and October 20, 1928, Serial Number 313,679, upon which the present invention is in the nature of an improvement.

Referring to the drawings, a well or pit 10 is illustrated wherein a solid foundation 11 of concrete, brick or other materials is provided, whereby a suitable base is afforded upon which to mount the mast sections. It is apparent that the base section of the mast may be placed directly on the ground level 60 or other support, without providing a well, but with the type of mast chosen for illustration, the well is more convenient because a concrete mixer of any known type may be positioned on the ground adjacent the edge of 65 the well, whereby to discharge the freshly mixed concrete to single or twin hoist buckets while in receiving position in the well, whence same may be elevated along or within the mast to a suitable height where they 70 are discharged into suitable chutes as is well known in the art.

A portion of the lifting mechanism utilized in erecting the mast sections comprises 75 a lifting frame 13 of inverted U-shaped form 80 having the cross member 14 and legs 15 and 16 formed of suitable piping, wooden posts or other convenient material, the former being preferable. Adjacent the free ends of 85 said legs, one or more tie braces 17 are provided for rigidly connecting the frame 13, as illustrated, so that a sturdy and rugged frame, capable of withstanding stresses and strains, is provided. A sheave 18 is suspended from cross member 14, and the cross member 17 has a winch 19 with a handle 20 mounted thereon. A cable 21 anchored to 90 and wound about said winch extends upwardly over said sheave 18 and downwardly to the load.

Although any convenient manner of erecting the base section 22 may be employed, the present improvements preferably contemplate that illustrated in Figs. 1 and 2, among 100 other reasons, because the pipe frame 13

may be utilized in this as well as in subsequently described steps. Suitable timbers 23 may be temporarily positioned across well 10 and the frame 13 mounted thereon and conveniently braced as by guys 24. The free end of cable 21 is then secured to the base section 22 to be erected, as at 21', whence the winch 19 is manually operated to elevate section 22 from the ground, over and above well 10 and placed in position on foundation 11 as seen in dotted lines (Figs. 1 and 2). The base section is temporarily guyed by wires 90 (see Fig. 5). It is notable that foregoing function of the winch and cable may be employed in subsequent erection steps, but, as hereinafter set forth, these elements preferably serve to change the position of the lifting mechanism.

The step in the method of erection illustrated in Figs. 3 and 4 may constitute a second step following the one above described, or if the base section 22 is positioned in another manner, the step now to be described may constitute the first step in the method. In any event, after section 22 is secured in place, the frame 13 and timbers 23 are removed. Another portion of the lifting mechanism comprising the support 25 is now mounted on a face of mast section 22. This support is in the form of a slidable frame having horizontal and vertical members and is provided with suitable shoes or rollers 25^a for sliding travel along the section 22. The horizontal portion of this support affords a surface 26 upon which the frame 13 is removably mounted, and also provides a platform for workmen in supervising the erection operations.

The frame 13 is illustrated in Figs. 3 and 4 in position on support 25, the parts being suitably braced to sliding support 25 by guy wires 24 and guy or tie rods 27. The cable 21, one end of which is anchored to winch 19 and wound thereabout, is now led down over sheave 28 on the support 25, upwardly over sheave 29 on the top of erected base section 22 and down therefrom to the support 25 where the free end of said cable 21 is anchored at 30. A counterweight 28^a is provided as illustrated. One or more operators may now stand on platform 25, and operate winch 19 by handle 20, thus winding in cable 21 and accordingly elevating the lifting mechanism, including frame 13 and support 25 (and the men thereon), to a position adjacent the top of base section 22 (see Fig. 5). While the foregoing method of raising the sliding frame is suggested for the reason that members already on hand are utilized to the exclusion of additional block and tackle, etc., it is apparent that any other manner of accomplishing the result may be practiced. The frame and appurtenances are now temporarily secured at the top of section 22 by bolts, pivoted latches or other

means for fixing platform 25 to the section 22. Safety latches 31 are provided as illustrated in Fig. 3. This section 22 may now be temporarily guyed by members 90 as seen in Fig. 5.

The members are now in position for raising the second or additional mast section 22^a. A cable 32, which was previously placed over sheave 18 on frame 13 is now paid out and the free end thereof anchored to new section 22^a at 33. As illustrated in Fig. 5, said cable extends from anchor 33 up and over sheave 18 and downwardly over sheaves 34 to a suitable hoisting engine or other power means (not shown). Upon the application of power to cable 32, section 22^a is gradually raised from the ground to the full line position of Fig. 5, where the removable rollers 35 and guides 36 on section 22^a contact the face of section 22. Said removable members may be omitted if desired, their provision however, facilitates travel of the section by preventing swinging of the section as well as insuring unobstructed ascent.

When the section 22^a reaches full line position (Fig. 5,) the operators upon platform 25 may transfer sheave bracket and sheave 29 from top of section 22 to the top of section 22^a, should the latter not already have been so equipped. Since platform 25 is now supported by the section 22, the operators thereon may remove the end of cable 21 from anchor 30, pass said cable over the sheave 29 on the new section and again anchor it at 30. Further pull upon cable 32, causes further ascent of section 22^a upwardly through aperture 37 in platform 25, until said section reaches a position where it is swung over, superposed on section 22 and bolted firmly in place thereon, as by tie plates 38. During this elevating process, the ascending sheave 29 (on the new section 22^a) causes cable 21 to be paid out from winch 19, whereby the platform and frame thereon are prepared to be elevated.

The platform may now be freed of its connection with section 22 and the winch 19 operated to raise same with frame 13 thereon, along the new section 22^a. Prior thereto or during this ascent, the attendants on the platform may remove rollers 35 and guides 36 and remove cable 32 from anchor 33. The platform, upon reaching the top of new section 22^a, may be connected thereto as previously described, (see Fig. 6) after which a guy strut 100 is secured near the top of the section as at plates 38 whereby guys 90 may be anchored thereto for steadyng the structure preparatory to raising additional section 22^b. The cable 32 is now lowered for elevating a third section 22^b, which process is carried out in the same manner as set forth with respect to section 22^a. Said section 22^b is secured in place (see dotted line position in Fig. 6) by the plates 39.

It is apparent that the lifting mechanism

may be elevated beyond the position illustrated in Fig. 6 by unfastening wires 27 until the mechanism is clear of guy strut 100 whence said wires may again be secured in place. Accordingly, the foregoing steps may be repeated, for positioning additional mast sections, whereby a mast of any desired height may be erected. The platform 25 carries a guy connection as an integral part of itself and is so proportioned that the standard guy connection may be placed in position and the guys transferred to it before raising the platform to the next position. When erection is completed, this platform 25 with its integral guy connection forms the top of the mast and top guy connection. The legs 25^B which extend down along the mast are so designed that they may be folded up out of the way of any other apparatus mounted on the mast, this feature permitting the entire height of the mast to be used for the distribution of materials.

The top of the mast is illustrated in Figs. 7 and 8. It is notable that the erection platform 25 is guided up the face of the mast which is normally and subsequently used by the sliding chute or hopper frame, while the mast sections are raised on the opposite face which is subsequently used by the hoist buckets. Accordingly in Figs. 7 and 8, the platform 25 is shown as bolted securely in place to form the mast top. The sheave 41 attached to said platform and provided with cable 42 affords the means for raising or lowering the chute or hopper sliding frame (not shown) to its proper position, while sheave 43 on the other side of said platform, through cable 44, affords the means for ascent and descent of single or twin buckets, as is known in the art. The pipe frame 13 may remain on the platform or be removed and lowered to the ground as desired.

As aforementioned, however, the platform 25, fixed to the mast top now serves, during the utilization of the mast, as a guy connection to which guy wires 92 are fastened. The mast is thus steadied and properly braced, as is known, and by employing the platform 25 in this connection it is seen that the usual cross members are dispensed with. Furthermore, said platform with its sheaves and cables takes the place of the usual cross member, whereby apparatus may be elevated and lowered along the inner or outer faces of the tower or mast.

It is also obvious that when it is desired to dismantle the mast, the platform 25 is on hand to perform its functions in the same manner, but in a reverse order, as it did during the erection operation. It is therefore notable that the dismantling of the mast may be accomplished by practicing the previously described steps in their reverse order.

Various modifications in the construction and arrangement of parts may be made with-

out departing from the scope of the present improvements. For example, the winch 19 may be operated to raise or lower the platform 25, in a manner other than that described. If desired, the cable 21, or other cable may be suitably arranged whereby a hoist engine or other power means, on the platform or on the ground, operates the cable for moving said platform and frame.

I claim:

1. An erecting mechanism for sectional mast plants comprising a support adapted to slide along a mast section, a vertical frame mounted on said support, means on said frame adapted to assist in elevating another mast section, said support constructed and arranged to afford passage of said other mast section through the limits defined by said support.

2. An erecting mechanism for sectional mast plants comprising a support adapted to slide along a mast section, a vertical frame removably mounted on said support, means on said frame adapted to assist in elevating another mast section, said support constructed and arranged to afford passage of said other mast section through the limits defined by said support.

3. An erecting mechanism for sectional mast plants comprising a support adapted to slide along a mast section, means for fixing said support to said mast section, a vertical frame mounted on said support, means on said frame adapted to assist in elevating another mast section, said support constructed and arranged to afford passage of said other mast section through the limits defined by said support.

4. An erecting mechanism for sectional mast plants comprising a support adapted to slide along a mast section, means for fixing said support to said mast section, a vertical frame removably mounted on said support, means on said frame adapted to assist in elevating another mast section, said support constructed and arranged to afford passage of said other mast section through the limits defined by said support.

5. An erecting mechanism for vertical masts comprising a support adapted to slide along an erected mast section, a vertical frame mounted on said support, means on said frame adapted to elevate a mast section, said support having an aperture adapted to afford passage of said mast section as the latter is elevated by said means.

6. An erecting mechanism for vertical masts comprising a support adapted to slide along an erected mast section, means for fixing said support to such erected section, a vertical frame mounted on said support, means on said frame adapted to elevate a mast section, said support having an aperture adapted to afford passage of said mast section as the latter is elevated by said means.

7. An erecting mechanism for vertical masts comprising a support adapted to slide along an erected mast section, means for fixing said support adjacent the top of an erected section, and means on said support adapted to receive guys, whereby said support serves initially during erection operations and subsequently as a guy anchor.

8. The method of erecting a sectional mast comprising erecting a base section, mounting a lifting mechanism on said base section, elevating said mechanism by power means thereon, anchoring said lifting mechanism to said erected section, attaching an additional section to be erected to said mechanism, elevating such additional section adjacent the top of said erected section, superposing said additional section on said erected section and securing together said sections.

9. The method of erecting a sectional mast comprising erecting a lifting mechanism, erecting a base section by said mechanism, transferring said lifting mechanism to said erected base section, elevating said lifting mechanism along said erected section, anchoring said lifting mechanism adjacent the top of said erected base section, attaching an additional section to be erected to said lifting mechanism, elevating such additional section adjacent the top of said erected section, superposing said additional section on said erected section and securing together said sections.

10. The method of erecting a sectional mast comprising erecting a lifting mechanism, erecting a base section by said mechanism, transferring said lifting mechanism to said erected base section, elevating said lifting mechanism along said erected section, anchoring said lifting mechanism adjacent the top of said erected base section, attaching an additional section to be erected to said lifting mechanism, elevating such additional section adjacent the top of said erected section, incorporating said additional section into the erected section, transferring said lifting mechanism to the now erected additional section and anchoring same adjacent the top of said section and repeating the operation.

11. The method of erecting a sectional mast comprising erecting a lifting mechanism, erecting a base section by said mechanism, transferring said lifting mechanism to said erected base section, elevating said lifting mechanism along said erected section, anchoring said lifting mechanism adjacent the top of said erected base section, attaching an additional section to be erected to said lifting mechanism, elevating such additional section adjacent the top of said erected section, incorporating said additional section into the erected section, transferring said lifting mechanism to the now erected additional section and anchoring same adjacent the top of

said section, and guying the completed mast by a portion of said lifting mechanism.

12. A convertible mast head for mast plants comprising a substantially horizontal member including a guy strut, folded frame members connected to said horizontal member, means for securing said member to a mast, said member being constructed and arranged to be freely slidable along a mast at will.

13. A combined erection platform and guy connection for mast plants comprising a slideable frame having a supporting surface and depending frame members, means for anchoring guy wires carried by said frame, said frame members having movable portions whereby said members may be temporarily shifted, and means for anchoring said frame to a mast.

14. In a mast plant for distributing loose materials, an erection platform adapted to be elevated and lowered on a mast, said platform having a supporting surface adapted to support erection elements, said platform also including pivoted frame members and means for anchoring guy wires, all so constructed and arranged whereby said platform may serve as a permanent guy connection for said mast after performing its function in the erection operation.

15. An erecting mechanism for sectional mast plants comprising a support adapted to slide along a mast section, means on said support to assist in elevating another mast section, said support having spaced members to afford passage of a portion of said other mast section therebetween.

Witness my hand this 14th day of November, 1928, county of Middlesex, State of New Jersey.

JAMES E. BUSHNELL.
